ATTORNEY

UNITED STATES PATENT OFFICE

JACOB J. KAGAN, OF LOS ANGELES, CALIFORNIA

DESIGN FOR A FINGER RING

Application filed August 11, 1930. Serial No. 36,624. Term of patent 3½ years.

To all whom it may concern:

Be it known that I, JACOB J. KAGAN, a citizen of the United States, residing at Los Angeles, in the county of Los Angeles and State of California, have invented a new, original, and ornamental Design for Finger Ring, of which the following is a specification, reference being had to the accompanying drawings forming a part thereof in which:

tive view thereof at a different angle to amplify the illustration.

The floral decoration shown on one of the solid panels is duplicated on the solid panel opposite to the one illustrated in detail.

I claim:

The ornamental design for a finger ring, substantially as shown and described.

In testimony whereof, I have hereunto set my hand at Los Angeles, California, this 6th day of August, 1930.

JACOB J. KAGAN,
